(57) **CLAIM**

What is claimed is the ornamental design for a feather duster, as shown and described.

DESCRIPTION

FIG. 1 is a front perspective view of the present invention.

FIG. 2 is a front elevational view of the present invention.

FIG. 3 is an inverted rear perspective view of the present invention; and,

FIG. 4 is an inverted rear elevational view of the present invention.

The broken lines shown are included for the purpose of illustrating environmental structure and form no part of the claimed design.

1 Claim, 4 Drawing Sheets

FIG. 3
